(57) **CLAIM**

The ornamental design for a sample sorting device as shown and described.

DESCRIPTION

FIG. 1 is a front elevational view of an embodiment of a sample sorting device showing our new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

FIG. 7 is a front elevational view of the base board portion of the sample sorting device thereof;

FIG. 8 is a rear elevational view thereof;

FIG. 9 is a left side elevational view thereof;

FIG. 10 is a right side elevational view thereof;

FIG. 11 is a top plan view thereof; and

FIG. 12 is a bottom plan view thereof.

FIG. 13 is an enlarged left side elevational view thereof;

FIG. 14 is an enlarged right side elevational view thereof;

FIG. 15 is a partially enlarged top plan view thereof at the area surrounded by the dot dash lines 15 of FIG. 11;

FIG. 16 is a partially enlarged top plan view thereof at the area surrounded by the dot dash lines 16 of FIG. 11;

FIG. 17 is a partially enlarged bottom plan view thereof at the area surrounded by the dot dash lines 17 of FIG. 12; and,

FIG. 18 is a partially enlarged bottom plan view thereof at the area surrounded by the dot dash lines 18 of FIG. 12.

The broken lines illustrating the sample sorting device or the portions thereof form no part of the claimed design.

(Continued)

The dot-dash broken lines in FIGS. 11 and 12 define the boundaries of the enlarged, partial views and form no part of the claimed design.
